UNITED STATES PATENT OFFICE.

MOSES B. ROGERS, OF HOLDEN, MAINE.

VIOLIN.

SPECIFICATION forming part of Letters Patent No. 246,911, dated September 13, 1881.

Application filed June 13, 1881. (No model.)

To all whom it may concern:

Be it known that I, MOSES B. ROGERS, of Holden, of the county of Penobscot and State of Maine, have invented a new and useful Improvement in Violins or Stringed Musical Instruments having Sounding-Boards; and I do hereby declare the same to be described in the following specification and represented in the accompanying drawings, which illustrate a violin provided with my invention—

Figure 1 being a top view, Fig. 2 a longitudinal section, and Fig. 3 a transverse section, of the body of the instrument with my improvement, which consists of what I term a "sonora" or wedge-shaped open box, combined with and arranged in the sounding-board substantially as represented.

This sonora is equally applicable to a bass or tenor viol, or to a viola or guitar, and even to various other stringed instruments, a violin with it being greatly improved in tone, as experience has demonstrated.

In the drawings, the sonora is shown, at A, as inserted in the sounding-board *a* and in the belly *b* of the violin *B*, and between the finger-

board *C* and the bridge *d* and beneath the strings *s* of the instrument. This sonora is open at its base, as represented, and is arranged so as to have such base in the plane of, or a little above, the upper surface of the sounding-board. The vertex of the sonora should not be in contact with the back *e* of the body of the instrument, to interfere with the vibrations of the sounding-board. The sonora being directly under the strings, the sounds produced thereby when the instrument is being played on by a person are more or less received within the sonora, and very advantageously modified by it.

I claim—

A violin or similar stringed musical instrument, in combination with an open box or sonora, as described, arranged within and projecting below the sounding-board of such violin or instrument, and having its base open toward the strings, all being substantially as set forth.

MOSES B. ROGERS.
